[57] CLAIM

The ornamental design for an electronic weighing scale
for dieters, substantially as shown and described.

DESCRIPTION

FIG. 1 is a front and top-right perspective view of an
electronic weighing scale for dieters showing our new
design;

FIG. 2 is a front elevational view thereof;

FIG. 3 is a right side elevational view thereof, the left
side being a mirror image thereto;

FIG. 4 is a rear elevational view thereof;

FIG. 5 is a top plan view thereof;

FIG. 6 is a bottom plan view thereof;

FIG. 7 is an enlarged front view of the console, the base
portions having been omitted for ease of illustration.
